(57) **CLAIM**

The ornamental design for a bowl as shown and described.

DESCRIPTION

FIG. 1 is a perspective view of a bowl according to our new design;
 FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

Conventional shading is illustrated for purposes of highlighting the line drawings, but forms no part of the claimed design.

The broken line showing of portions of the bowl are included for the purpose of illustrating environmental structure and form no part of the claimed design.
